INVENTOR

UNITED STATES PATENT OFFICE.

WILLIAM H. TUFTS, OF WASHINGTON, DISTRICT OF COLUMBIA.

CARRIAGE-BUTTON.

SPECIFICATION forming part of Letters Patent No. 252,156, dated January 10, 1882.

Application filed June 17, 1881. (No model.)

To all whom it may concern:

Be it known that I, WM. HENRY TUFTS, a citizen of the United States, residing at Washington, District of Columbia, have invented a new and useful Carriage-Button, of which the following is a specification.

The object of my invention is to overcome the difficulty experienced by owners and users of carriages in keeping the curtains securely in their place when buttoned.

This device consists of a movable head to a button, working from a vertical to a horizontal position, constructed in the manner hereinafter presented.

15 The accompanying drawings illustrate the construction and relation to each other of the different parts of the button.

Similar letters refer to similar parts therein.

Figure 1 is a section of a curtain secured 20 with the button B; Fig. 2, a vertical view of the button B complete and ready for use; Fig. 3, a vertical view of the button B without the sleeve b; Fig. 4, a vertical section of the complete button B, showing the position of the 25 different parts when put together; Fig. 5, a perspective view of the button-head B', with stem f and slot e; Fig. 6, a view of the modification of the button B; Fig. 7, a small section of a curtain, showing the shape of button-hole when used with my invention.

Letter A designates a section of a carriage-curtain; a, the screw attached to the body of the button B; a', the swivel to the modified button; B, the button complete; B', the button-head independent of stem f and slot e; b, the sleeve covering the body c; c, the button-hole made to fit the button B; c, the body of the button B; D, a single-tree with modified button attached; d, the pin in position in the button-body c; d', the pin in position in the modified button; E, the ferrule to modified button; e, the slot in stem f of button-head B'; e', the slot in stem of modified button-head; f, the stem of button-head B'; f', the stem of modified button-head.

45 The button, after being screwed or driven (according to its construction with screw or tap-pin) into its place on the carriage, should be turned to a horizontal position, and the button-hole of the curtain pressed over the button-head and onto the body of the button. The

button-head should then be turned to a vertical position, bringing it at right angles with the button-hole in the curtain, thereby securely confining the latter in its place at that point. 55

In fixing the button in its place on the carriage the end of the screw should be inserted into the wood and the button-head turned to a horizontal position, when it will stop against the pin d, inserted into the body c of the button B and working in the slot e, cut in the stem f of the button-head B'.

The pin d is a small piece of round metal, made to fit into a hole drilled in the button-body c, and made longer or shorter, as required. 60

To the button-head B' is attached a slotted stem, as shown in Fig. 5 of the drawings. This stem f is to be put into the open end of the button-body c with the slotted side toward the hole in the button-body. The pin d is now inserted into the hole, and, being long enough, it reaches down into the slot e, and, bearing upon both sides of it, holds the button-head in place. 70

The slot e in stem f is cut exactly long enough to allow a movement of the button-head from a vertical to a horizontal position, and vice versa. When the button-head is moved its stem revolves in the button-body, but its revolution is limited by the pin d. When the button-head is upright one end of the slot rests against the pin d, preventing any movement of the former to the left. When the button-head is in a horizontal position the other end 80 of the slot rests against the pin d, and the forward movement is stopped. Here is where the power that forces the screw a into the wood acts upon all parts of the button at the same time. If, then, the end of the slot in stem of 85 button-head rests solidly against the pin d when the button-head is in a horizontal position, (the pin being firmly fixed in the button-body,) it is obvious that all parts of the button must turn at the same time, if turned at all, 90 and as the screw is permanently attached to the button-body the latter will be drawn up to the wood as the screw penetrates. 95

To withdraw the button, reverse the operation, turning the button-head to an upright or vertical position, and a few turns to the left will unscrew it. 100

The slot *e* is shown in the stem *f* of the button-head; but it is obvious that the position may be reversed by cutting the slot in the body of the button and fixing the stop-pin *d* in the stem of the button-head.

The metal sleeve *b* is of twofold importance—first, to prevent the pin *d* from working out, and, second, as a means of obtaining sufficient pressure against the button-head to prevent its moving in any manner while the carriage is in motion. These results are accomplished by sliding the sleeve *b* over the body *c* of the button *B*. Then the button is screwed into its place on the carriage and the sleeve *b* is forced against the wood and under edge of the button-head *B'* simultaneously. This adjustment also produces a friction by means of which the button-head may be made to turn hard or easy, as the pressure of the edge of the sleeve *b* is greater or less upon it.

The sleeve *b* may have a swelled or molded edge, roughened so that the button-head can have a wider as well as a rugged surface to turn against. The under edge of the button-head may also be indented to correspond with the edge of the sleeve.

A washer, of rubber or other elastic material, should be placed between the wood and the button before the latter is put in place.

To prevent rattling, a piece of rubber tubing may be placed between the stem of the button-head and the inside of the button-body *c*.

The advantages claimed for this device over other carriage-buttons are as follows:

First, when a curtain or trace is once buttoned it must remain so until unbuttoned by some one.

Second, there is less wear and tear of the button-hole and less liability to get out of

shape when made to fit this button than in a straight-slit button-hole of the usual construction.

In applying my invention for use on single-trees as a trace-button the button-head *B'* will be swiveled in the inside of a ferrule, as at *E*, Fig. 6. The ferrule *E* is to be driven over the end of the single-tree *D*, formed with a shoulder, and secured by a pin or screw.

The claim I make for my invention, and for which I ask Letters Patent, is—

1. The combination, in a carriage-button, of the movable head *B'*, provided with stem *f* and slot *e*, with the hollow body *c* and the pin *d*, as and for the purpose herein set forth.

2. The combination, in a carriage-button, of the movable head *B'*, provided with stem *f* and slot *e*, with the hollow body *c*, the pin *d*, and the screw *a*, as and for the purpose specified.

3. The combination, in a carriage-button, of a body, *c*, a head, *B'*, movable therein, a screw-stem, and a sleeve, *b*, as and for the purpose set forth herein.

4. The combination, in a carriage-button, of the movable head *B'*, provided with stem *f* and slot *e*, with the hollow body *c*, the pin *d*, and the sleeve *b*, substantially as set forth.

5. The combination, in a carriage-button, of the movable head *B'*, provided with stem *f* and slot *e*, with the hollow body *c*, the pin *d*, the screw *a*, and the sleeve *b*, as and for the purpose herein set forth.

WM. HENRY TUFTS.
